RULING MACHINE

Albert Broadmeyer, Harrisburg, Pa., assignor to
W. O. Hickok Manufacturing Company, Harris-
burg, Pa., a corporation of Pennsylvania

Application July 7, 1931, Serial No. 549,283

11 Claims. (Cl. 33—34)

In ruling apparatus, particularly that of the dual L-type in which two ruling machines are employed that are located at right angles one to the other, with the second machine receiving the ruled sheets from the first machine, an adjustable stop at the corner or delivery end of the first machine is usually employed, this stop being made adjustable so that it will properly position sheets of different sizes in relation to their introduction into the second machine. In the second machine, as is well known to those skilled in the art, guides are employed for the sheets that are moved from the first machine and are carried through the second. The adjustment of the stop in the corner, or at the delivery end of the first machine has heretofore required the adjustment of the guides in the second machine, thus making an alteration a relatively intricate problem as the guides are ordinarily substantially aligned with the stop.

The object of the present invention is to provide a structure in which the stop and therefore the guides may be relatively fixed, and to provide conveying means that is adjustable toward and from the stop so as to insure delivery of sheets of different sizes thereagainst. To a very great extent therefore this eliminates the necessity of an adjustment throughout the second machine.

In the accompanying drawings:

Figure 1 is a plan view of a dual-L ruling machine with the preferred embodiment of the invention therein.

Figure 2 is a cross sectional view on the line 2—2 of Figure 1.

Figure 3 is a cross sectional view on the line 3—3 of Figure 1.

Figure 4 is a longitudinal sectional view schematic in its character through the first machine.

Figure 5 is a horizontal sectional view and is taken on the line 5—5 of Figure 3.

Figure 6 is a bottom plan view of the corner mechanism taken on the line 6—6 of Figure 3.

Figure 7 is a perspective view of the adjustable mounting for the roller at the discharge end of the delivery conveyor.

Figure 8 is a detail view on the line 8—8 of Figure 1.

Figure 9 is a detail sectional view on the line 9—9 of Figure 3.

Figure 10 is a detail view taken on the line 10—10 of Figure 2.

Figure 11 is a detail sectional view of the tightener for the delivery belt on the second machine illustrated in Figure 2.

In the structure disclosed, two machines are illustrated designated respectively 12 and 13 located at right angles to each other and each being provided with suitable pen beams or sheet marking implements designated respectively 14 and 15. These instrumentalities and the mechanisms for operating them are well known, and it is believed need no further exposition. Suitable gates, indicated at 16 and 17, serve to control the passage of the sheets to the ruling devices.

Referring particularly to Figure 4, it will be noted that the gate 16 and ruling devices 14 are located over the usual table 18 and the sheets are carried to the gate 16 and under the ruling devices 14 by an endless cloth or belt that has an upper rearwardly moving stretch 19 operating over the table and passing around a rear roller 21. A lower stretch 22, moving forwardly from the roller 21 beneath the table 18, extends around a series of rollers 23 at the front end of said table. Endless cords or strings 24, operating around rollers 25, have lower stretches 26 that cooperate with the stretch 19 and clamp the sheets carried by said stretch 19. The sheets that are carried by the stretch 19 of the cloth are brought around the roller 21 and are carried forwardly against the under face of the stretch 22 of the cloth. In order to maintain the sheets against said stretch 22, endless cords or strings 27 cooperate with the stretch 22 extending around the roller 21 and around a roller 28 in advance of the lowermost roller 23. The strings are guided around the roller 21 by an upper idler roll 29 and said strings are directed from the roller 28 rearwardly and downwardly by a roller 30 to another guide roller 31, from whence said strings pass back to the roller 29.

The sheets leave the front end of the stretch 22 of the cloth and are directed by the cords 27 to another endless conveyor cloth 32 that passes around a guide roller 33 and around the front side of the roller 38. This conveyor cloth 32 has a rearwardly and downwardly moving stretch 34 on which the sheets are held by the cords 27, and the rearwardly running stretch 34 of this endless conveyor 32, ends at a roller 35 located below and in rear of the guide roller 33 for the strings 27. From the roller 35 the conveyor extends forwardly in the form of a stretch 36 passing around guide rollers 37, and thence to a guide roller 38 from which the cloth returns to the roller 33. The guide rollers 37 are thus in a forwardly moving lower stretch of the cloth and a loop is formed in said cloth at 39, this 55

loop suspending a relatively heavy take-up roller 40.

With the structure as thus far described, it will be noted that the sheets after passing the 5 ruling devices, are thus carried forwardly between the stretches 22 of the first cloth and the underlying stretches 27 of the strings, and that when said sheets reach the front end of the machine they are again turned downwardly and 10 rearwardly and rest upon the stretch 34 of the cloth 32, being held thereagainst by the strings 27. The sheets are delivered from the stretch 34 of the cloth at the roller 35 and in order to insure this delivery, rollers 41 are employed that 15 are located in rear of the roller 33 and between which the cords pass to the guide roller 31. When delivered from the stretch 34 of the cloth they are carried by tapes 42 rearwardly until they strike a stop bar 43 placed across their 20 path when on the tapes 42. The bar 43, as will be noted particularly by reference to Figure 3 is mounted on the rods 44 that pass through horizontal holding guide collars 45 and these rods may be clamped by set screws 46. The stop 25 is thus made adjustable, but for ordinary purposes, having once been adjusted, it does not thereafter have to be materially altered.

The sheets are thus delivered into the corner of the apparatus and are brought against the 30 stop 43. From this point they are fed into the second machine 13. For this purpose, a suction roller 47 is employed, which is operated in a well known manner periodically to move the sheets at right angles to their path of delivery 35 against the stop 43 and carry them to an inclined conveyor 48 that delivers them to the gate 17 of the second machine, this gate operating periodically in a manner well understood. From this gate they move under the ruling devices 15 of 40 the second machine, being carried by an endless cloth 49. Cooperating with the upper stretch of this cloth are endless cords 50 that hold the sheet thereupon, and cooperating with the forwardly moving stretch 49 are other cords 51 that 45 deliver the sheets to a lower second cloth 52 arranged much on the order of the cloth 34 already described. Cooperating with the cloth 52 are stretches of the cords 51, and this cloth and the cords deliver the ruled sheets to rollers 53 that in turn discharge them into a layboy 54. The cloth 52 instead of being kept taut, as is 50 the cloth 36 by a weighted take-up roller 40, passes around a roller 55 which as shown in Figure 11 has mountings in adjustable boxes 56. These are engaged by adjusting screws 57.

Referring now again to the first machine, and particularly the delivery end of the stretch 34 of the cloth 32 with respect to the stop 43, instead of it being necessary as heretofore to adjust 60 this stop 43 to various sizes of paper, the delivery end of the cloth 32 is adjustable toward and from this stop by making the roller 35 transversely adjustable. Means in the present embodiment for effecting this is shown more particularly in Figure 7. The roller 35 around which the cloth 32 passes, has bearings in boxes 58 carried by the ends of horizontal racks 59. These racks are slideable in guideways 60 mounted on the frame of the machine by brackets 61. Journalized 65 in said brackets is a shaft 62 having a suitable handle 63. The shaft carries pinions 64 in mesh with the racks. Obviously by turning the shaft 62 the racks are moved, thereby moving the boxes 58 and carrying the roller 35 toward and 70 from the stop 43. The roller is held in its ad-

justed position by any suitable means, as set screws 65 mounted in the guideways 60 and bearing against the racks. The rollers 30 and 41 are preferably carried by brackets 66 formed upon the boxes 58. It will be noted particularly by 10 reference to Figure 4 that any adjustment of the roller 35 either toward the stop 43 or away from it, and which varies the length of the stretches 34 and 36 of the cloth 32, is allowed for by the loop 39 and the rising and falling of the take-up roller 40. This roller 40 as shown in Figure 9, has its gudgeons 67 journaled in boxes 68 that are vertically movable in guideways 69.

With this structure, it will be evident therefore that having once positioned the stop bar 43 and 15 alined the guides through the second machine (one of said guides being shown at 76 in Figure 1), sheets that are properly brought against said stop, will always pass through the second machine in correct alinement. If smaller sheets 20 are to be ruled at any time, instead of adjusting the stop 43 and the guides through the second machine, it only becomes necessary to move the roller 35 toward the stop 43 (see Figure 4) so that the delivery takes place closer to the stop 25 43. If it is desired to pass larger sheets through the machine than those which have been ruled in a previous lot, the roller 35 is moved away from the stop. Irrespective of this adjustment of the roller 35, the active stretch 34 of the cloth 30 32 is kept properly taut by reason of the take up roller 40.

From the foregoing, it is thought that the construction, operation and many advantages of the herein described invention will be apparent 35 to those skilled in the art without further description, and it will be understood that various changes in the size, shape, proportion and minor details of construction may be resorted to without departing from the spirit or sacrificing any 40 of the advantages of the invention.

What I claim, is:

1. In a ruling machine, the combination with 45 ruling devices, of a stop against which the sheets are brought after passing the ruling devices, a conveyor for carrying the sheets to and against the stop, said conveyor having a receiving end, a support for said receiving end, a second endless conveyor for delivering the sheets to the first conveyor and having a sheet carrying stretch and a 50 return stretch, and means for supporting the carrying and return stretches of the second conveyor at its delivery end above the support and receiving end of the first conveyor and permitting their adjustment thereover toward and from 55 the stop.

2. In a ruling machine, the combination with 60 ruling devices, of a stop against which the sheets are brought after passing the ruling devices, a conveyor for carrying the sheets to and against the stop, said conveyor having a receiving end, a roller around which the receiving end passes, a second endless conveyor for delivering the sheets to the first conveyor and having a sheet carrying stretch and a return stretch, a roller 65 around which the endless conveyor passes at its delivery end, carrier means on which the roller is journalized and which supports said roller above the roller of the first conveyor, and a mounting for the carrier means located at the receiving end 70 of the first conveyor and on which said carrier means is adjustable, said mounting permitting the adjustment of the carrier means and the positioning of the roller of the second conveyor at different distances therefrom and to different 75

positions over the first conveyor and above the roller thereof at different distances from the stop.

3. In a ruling machine, the combination with 5
ruling devices, of a stop against which the sheets
are brought after passing the ruling devices, a
conveyor for carrying the sheets to and against
the stop and including a roller around which the
receiving end of said conveyor passes, a second
10 endless conveyor independent of said roller for
delivering the sheets to the first conveyor and
having a sheet carrying stretch and a return
stretch, a roller around which the endless con-
veyor passes at its delivery end, said latter roller
15 being movable in a path above the first roller
and above the receiving end of the first conveyor
carrier means on which the second roller is jour-
naled, a mounting for the carrier means located
20 at the receiving end of the first conveyor and on
which said carrier means is adjustable, said
mounting permitting the adjustment of the car-
rier means and the positioning of the roller at
different distances therefrom and to different
25 positions over the first conveyor at different dis-
tances from the stop, and means for moving the
carrier means.

4. In a ruling machine, the combination with
ruling devices, of a stop against which the sheets
are brought after passing the ruling devices, an
endless conveyor for carrying the ruled sheets
30 toward the stop, said conveyor including a sheet
carrying stretch and a return stretch and termin-
ating short of the stop and having a delivery
end adjustable toward and from the stop, means
for mounting the delivery end of the conveyor
35 to permit such adjustment, a take-up for the end-
less conveyor located in the return stretch in ad-
vance of the delivery end thereof, and another
conveyor that receives the sheets from the said
first conveyor and carries them against the stop,
40 said latter conveyor having a mounting for its
receiving end independent of the first conveyor
and located beneath the sheet carrying and re-
turn stretches of the first conveyor and behind
the take-up.

5. In a ruling machine, the combination with
ruling devices, of a conveyor cloth carrying
sheets to be ruled past the same, a stop for the
ruled sheets, a second conveyor cloth receiving
50 the sheets from the first and having an upper
sheet carrying stretch and a lower return stretch,
said second conveyor having a delivery end
spaced from the stop, a roller about which said
conveyor passes at its delivery end, means ad-
justably supporting the roller and permitting its
55 placement at different distances from the stop,
a take-up on the lower stretch of the second
conveyor in advance of said roller and being
freely movable on the adjustment of the roller,
and a third conveyor for moving the sheets from
60 the delivery end of the second conveyor to the
stop, said third conveyor having a roller for its
advance or receiving end beneath the upper and
lower stretches and the roller of the second con-
veyor and behind the take-up.

6. In a ruling machine, the combination with
ruling devices, of a stop for the sheets ruled by
said devices, a conveyor for moving the sheets
65 toward the stop, and sheet retaining means co-

acting with the conveyor and extending beyond
its delivery end, said conveyor having a delivery
portion adjustable to different positions from the
stop and along the sheet retaining means.

7. In a ruling machine, the combination with 5
ruling devices, of a stop for the sheets ruled by
said devices, a conveyor for moving the sheets
to the stop, a second conveyor for delivering the
sheets to the first conveyor, and sheet retaining
10 means extending along both conveyors, said sec-
ond conveyor having a sheet delivery portion
movable between the first conveyor and the sheet
retaining means to different distances from the
stop.

8. In a ruling machine, the combination with 15
ruling devices, of a stop for the sheets ruled by
said devices, a conveyor for moving the sheets
to the stop, a second conveyor for delivering
sheets to the first conveyor and having a sheet
carrying stretch, sheet retaining means overlying
20 the sheet carrying stretch and the first con-
veyor, said second conveyor having a sheet de-
livery portion movable between the first conveyor
and the sheet retaining means to different dis-
tances from the stop, and guiding means for the
25 sheet retaining means adjustable with the said
delivery end.

9. In a ruling machine, the combination with
ruling devices, of a stop for the sheets ruled by
said devices, a conveyor for carrying sheets to 30
and against the stop, means for moving the ruled
sheets from the ruling devices to the conveyor
including an endless conveyor cloth having an
upper sheet carrying stretch and a lower return
35 stretch, a take-up in the lower return stretch,
endless sheet directing cords extending along the
sheet carrying stretch and over the first men-
tioned conveyor, said conveyor cloth having a
delivery end between the first conveyor and the
40 cords and spaced from the stop, a roller for the
delivery end of the conveyor cloth, a bracket
mounting for the roller adjustable toward and
from the stop and carrying said roller and de-
livery end with it, and guide means for the cords
45 mounted on and adjustable with the bracket
mounting.

10. In a ruling machine, the combination with
ruling devices, of a stop for the ruled sheets,
means for moving the sheets in an angular direc- 50
tion away from the stop, and means for convey-
ing the sheets from the ruling devices to the
stop, including sheet retaining cords that move
along the path of the sheets and directly above
the stop.

11. In a ruling machine, the combination with 55
ruling devices, of a stop for the ruled sheets,
means for moving the sheets in an angular direc-
tion away from the stop, and means for convey-
ing the sheets from the ruling devices to the stop
including a conveyor that brings the sheets suc- 60
cessively against the stop and another conveyor
that delivers the sheets to the first mentioned
conveyor, and sheet retaining cords that coop-
erate with the second conveyor to hold the sheets
thereagainst, said retaining cords extending 65
along and above the first mentioned conveyor.

ALBERT BROADMEYER.
